[57] CLAIM

The ornamental design of a hydraulic powered combined pipe and tubing straightener, substantially as shown and described.

DESCRIPTION

FIG. 1 is a reduced isometric view of a hydraulic powered combined pipe and tubing straightener showing my new design, the portions of the tubing are shown broken away to indicate indeterminate length;

FIG. 2 is a side elevational view taken from the rear of FIG. 1, the handle and hydraulic pump being omitted for ease of illustration;

FIG. 3 is a top plan view of FIG. 2;

FIG. 4 is a bottom plan view of FIG. 2;

FIG. 5 is an end elevational view taken from the left of FIG. 2;

FIG. 6 is an end elevational view taken from the right of FIG. 2.

FIG. 2

FIG. 3

FIG. 4

FIG. 5

FIG. 6
